CLAIM

The ornamental design for a display screen with graphical user interface, as shown and described.

DESCRIPTION

FIG. 1 is a front view of the first image in a sequence of a display screen with graphical user interface showing our new design according to a first embodiment;

FIG. 2 is a front view of the second image thereof;

FIG. 3 is a front view of the third image thereof;

FIG. 4 is a front view of the fourth image thereof;

FIG. 5 is a front view of the fifth image thereof;

FIG. 6 is a front view of the sixth image thereof;

FIG. 7 is a front view of the first image in a sequence of a display screen with graphical user interface according to a second embodiment;

FIG. 8 is a front view of the second image thereof;

FIG. 9 is a front view of the third image thereof;

FIG. 10 is a front view of the fourth image thereof; and,

FIG. 11 is a front view of the fifth image thereof.

All text, characters, and numbers in the drawings illustrate portions of the graphical user interface that form no part of the claimed design. The evenly-spaced broken lines are included for the purpose of illustrating elements of the graphical user interface and the display screen that form no part of the claimed design. The subject matter of this patent includes a process or period in which an image sequentially transitions into another image. This process or period forms no part of the claimed design.
